UNITED STATES PATENT OFFICE.

ERNEST C. COOK, OF CHICAGO, ILLINOIS.

AUTOMATIC STOP FOR PHONOGRAHS.

1,324,190.

Specification of Letters Patent.

Patented Dec. 9, 1919.

Application filed March 1, 1919. Serial No. 280,040.

To all whom it may concern:

Be it known that I, ERNEST C. COOK, a citizen of the United States, residing at Chicago, in the county of Cook and State of Illinois, have invented a certain new and useful Improvement in Automatic Stops for Phonographs, of which the following is a full, clear, concise, and exact description, reference being had to the accompanying drawings, forming a part of this specification.

This invention relates to improvements in automatic stops for phonographs.

The object of the invention is to provide a manually set, simple and sensitive device for automatically stopping the turning of a phonograph record when the reproducing needle has reached the end of the reproducing portion of the record.

Another object of the invention is to provide an automatic stop of the type above indicated which may be manufactured at comparatively small expense in units and readily applied to phonographs now on the market and not heretofore equipped with such stops.

In the drawing forming a part of this specification, Figure 1 is a broken view, partly in top plan and partly in horizontal section, of portions of a record-carrying table, reproducing mechanism, tone arm and automatic stop in connection therewith. Portions of the table and record are broken away in order to more clearly illustrate the automatic stop mechanism. Fig. 2 is an enlarged, vertical, sectional view taken substantially on the line 2—2 of Fig. 1. And Fig. 3 is a vertical, detail, sectional view taken substantially on the line 3—3 of Fig. 1, and illustrating more particularly parts of the automatic stop in end elevation.

In said drawing, 10 denotes the motor board of a phonograph such as is found in those types known as "cabinet phonographs" and to the under side of which motor board the motor is generally secured. The rotating table for carrying the record is indicated at 11, the same being rotatable about the center indicated at 12. As customary, the table 11 is suitably covered on the top thereof with a layer 13 of felt or other material and the record 14 is applied thereon. The table is formed in the usual manner with a depending outer annular flange 15, the lower edge of which is disposed a short distance above the upper surface of

the motor board 10. The dotted members 16 indicate conventionally a reproducing mechanism and 17 the coöperating tone arm, the latter being swiveled about a vertical axis and supported by any suitable means as from the bracket 18 carried by the sleeve member 19 into which the lower enlarged end of the tone arm is projected.

In carrying out my invention, I provide a small plate 20 of elongated form as shown most clearly in Fig. 1, the same being adapted to be attached to the motor board 10 by any suitable means such as the screws 21—21. The plate 20 and its associated parts are located in the position shown in Fig. 1 with respect to the table and for the greater part underneath the table. Mounted on the plate 20 is a bell crank lever pivoted at 22. The bell crank lever has a relatively short arm 23 projecting under the flange 15 of the table and an elongated arm 24, the ratio of said arms 23 and 24 being approximately as 1:3 for the purpose of rendering the tripping action extremely sensitive, as hereinafter explained.

Also mounted on the plate 20 about a pivot 25 is a cam plate 26 having a handle 27 by which it may be manually set. On the side adjacent the axis of the tone arm, the plate 26 is provided with a relatively narrow shoulder as indicated at 28 so located that it will engage with the extreme end 29 of the arm 24 of the bell crank herefore mentioned. The handle 27 is extended out from under the table so as to be readily accessible to the operator, as will be understood. The plate 26 carries a suitable friction brake element on its upper face as indicated at 30, the latter being of felt or other suitable material and extending upwardly sufficiently so that it will engage the inner face of the depending flange 15 of the table when the stop is tripped, as hereinafter explained.

The cam plate 26 has attached thereto one end of a tension spring 31, the other end of the spring 31 being attached to a suitable pin 32 carried by the plate 20. As shown most clearly in Fig. 1, a line drawn from the pin 31 to the pin 32 on the cam plate 26 and to which the ends of the spring 31 are attached, passes slightly to one side of the axis of rotation of the cam plate 26 so that, when relieved of the restraining influence of the arm 24 of the bell crank, the cam plate 26 will be rotated in a counterclock-

wise direction until the clutch element 29 thereon engages the inner face of the flange 15 of the table and stops the latter so that further rotation of the table and record is prevented.

5 Another spring 33 is provided having one end thereof attached to said pin 31 and its opposite end preferably hooked into an opening 34 formed in the bell crank arm 24, said spring 33 being also under tension 10 in order to hold normally the end 28 of the arm 24 in the position shown in Fig. 1. The plate 20 is preferably provided with a small upstanding arm 35 located as shown 15 most clearly in Figs. 1 and 3 and in which is threaded a set screw 36. The set screw 36 is located in the same plane as the arm 24 of the bell crank and is so adjusted as to limit the outward movement of the arm 24 after it has been tripped from the cam 20 plate 26 and is designed to prevent oscillation or vibration of said arm 24 when it has been tripped from the cam plate 26, thereby eliminating undesirable noise.

25 To effect the release of the cam plate 26, I provide a bracket 37 fitting and screwed to a suitable adjacent portion of the enlarged end of the swiveled tone arm as by the screws 38—38. Said bracket 37 has an 30 arm 39 which is extended first downwardly in a vertical direction and then outwardly in a horizontal direction as indicated at 40. Pivotally attached to the lower end 40 of the bracket above described, is a right angled lever having a short arm 41 and a longer arm 42. Said lever is pivotally attached to the portion 40 of the bracket by an adjustable friction pivot pin shown most 35 clearly in Fig. 2, said friction pivot pin 40 comprising an interiorly threaded sleeve 43 having an annular shoulder 44 at its lower end, a tightening screw 45 and a friction disk 46. The disk 46 is preferably cup-shaped and is engaged by the head of the 45 screw 45 so as to frictionally press against the lever 41—42 and hold the latter when set against any ordinary pressure. The lever 41—42 is located in the same horizontal plane as the bell crank 23—24 and with 50 the angled portion indicated at 47 so located as to engage and trip the outer end of the short arm 23 of the bell crank.

55 As is well known, the reproducing grooves of the ordinary disk record are placed very close together, approximately 1/100th of an inch in actual practice, and it is therefore evident that the automatic stop or trip must be delicately set if it is to effect the stoppage of the record and motor when the reproducing needle has reached the end of the reproducing grooves. In operating my device, the cam plate 26 and bell crank 23—24 are 60 manually set as shown in Fig. 1. The operator then places the reproducing needle indicated at 48 in the last sound reproducing

groove or next inner blank groove while the parts are stationary and, with the reproducing apparatus and tone arm in this position, the operator manually sets the lever 41—42 so that the shoulder 70 47 thereof just contacts with the arm 23 of the bell crank. With the parts thus set, the record is played in the usual manner by moving the reproducing mechanism to the outer edge of the record and placing the 75 needle in the grooves and releasing the table by the usual manually operated brake device (not shown). As the reproducing mechanism and tone arm follow the record grooves inwardly toward the center of the 80 disk, it is evident that the shoulder 47 of the lever 41—42 will approach the short arm 23 of the bell crank and finally will trip the latter as the needle 48 reaches the last sound reproducing groove. As the bell crank 85 23—24 is stripped and swung in a counter-clockwise direction, the end 28 of the long arm of the bell crank will be disengaged from the shoulder 27 of the cam disk 26 and the latter will then be free for rotation under the influence of the tension spring 30, thus throwing the brake element 29 against the flange 15 of the table and stopping further movement thereof.

90 By employing the relatively short arm 23 and relatively long arm 24 of the bell crank, it is evident that I render the device extremely sensitive since movement of the short arm 23 for a distance of say 1/100th of an inch will produce substantially three 100 times that amount of movement at the end 28 of the arm 24. Consequently, if the mechanism is set correctly or even approximately correctly before starting to play the record, the automatic stop will be brought into effective action substantially instantaneously 105 when the reproducing needle 48 reaches the innermost reproducing sound grooves of the record and will prevent operation of the table and record after the needle has passed 110 beyond the sound reproducing grooves. It is evident that the lever 41—42 is so formed as to permit accurate adjustment thereof manually by the operator and furthermore the parts are so designed and assembled that 115 they may be readily manufactured at comparatively small expense and the two units attached to the motor board and tone arm, respectively, with a minimum amount of labor. The construction of the stop is also 120 such that it may be applied to all of the disk playing types of phonographs without modification of the latter, thus increasing the utility of the numerous phonographs now 125 on the market not equipped with such automatic stops.

130 Although I have herein shown and described what I now consider the preferred manner of carrying out the invention, the same is merely illustrative and I contem-

plate all changes and modifications that come within the scope of the claim appended hereto.

I claim:

- 5 An automatic stop for phonograph tables comprising, in combination, a base plate adapted to be attached to a fixed part of the phonograph, a brake element adapted to engage with the rotary phonograph table, 10 an oscillatory plate carrying said brake element and pivoted on said base plate and having a stop shoulder and a setting handle, a spring for actuating said oscillatory plate to apply said brake element, a bell crank 15 lever pivoted on the base plate and having a long arm engageable with said stop shoulder to hold the brake inoperative and having a short arm rigid with said long arm and extending away from the center of the 20 rotary table, a spring for yieldingly hold-
- ing said long arm of the bell crank lever engaged with said stop shoulder, a bracket adapted to be secured to the tone arm, a lever having a shoulder for engaging said short arm of the bell crank lever to release 25 its long arm from said stop shoulder and having a setting handle, and a pivotal friction joint connecting said shouldered lever with said bracket and adapted to be turned by the handle of the former and to overcome by its friction the tension of the spring which actuates the long arm of the bell crank lever.

In witness that I claim the foregoing I have hereunto subscribed my name this 13th 30 day of Feb., 1919.

ERNEST C. COOK.

Witness:

KARL BAACKES.
